CLAIM

The ornamental design for the miniature baseball bat stand, as shown and described.

DESCRIPTION

FIG. 1 is a top front and left perspective view of a miniature baseball bat stand showing my new design; FIG. 2 is an enlarged top plan view thereof; FIG. 3 is an enlarged bottom plan view thereof; FIG. 4 is an enlarged left side elevational view thereof, the right side being a mirror image of that shown; and, FIG. 5 is a top, front and left side perspective view of an alternate embodiment thereof, the difference residing in the width of the horizontal elements, and the number of apertures therein.
